PAGE 2

Fig. 2

Fig. 3

Fig. 4

Fig. 5

FIGURE 1 is a perspective view of a STOL utility aircraft, showing my new design;

FIGURE 2 is a side elevational view thereof;

FIGURE 3 is a top plan view thereof;

FIGURE 4 is a front elevational view thereof; and

FIGURE 5 is a bottom plan view thereof.

The broken line showing of cargo in FIGURES 2, 3, 4 and 5 is for illustrative purposes only.

I claim:

The ornamental design for a STOL utility aircraft, as shown and described.
